RECOIL AMPLIFIER DEVICE

Aage Frederik Christian Henckel,
Hellerup, DenmarkApplication July 25, 1946, Serial No. 686,236
In Denmark April 30, 1946

3 Claims. (Cl. 89—14)

1

The invention relates to a recoil amplifying device for automatic firearms with interchangeable barrel.

In later types of such arms, the barrel jacket is open on top, and the change of barrel is effected in such manner that, being connected to the front part of the receiver by a sort of bayonet joint or in like manner, the barrel is turned initially by means of handle attached to the barrel at a certain angle around its axis, until there is no connection between the barrel and the receiver, and next the barrel is drawn forwards and free of the receiver, after which it is finally removed.

It has hitherto not been practicable to change a barrel in this manner by automatic firearms with recoil amplifiers, inasmuch as the latter, forming the front bearing of the barrel, has until now always been rigidly connected to the jacket, whereby it prevented the rear of the barrel from being raised.

This drawback has been remedied by the recoil amplifier according to the invention, as in accordance hereto the recoil amplifier is equipped at its rear with two horizontal pivots arranged diametrically opposite one another, by which pivots it rests in bearings in front extensions of the sidewalls of the barrel jacket.

Preferably the pivots of the recoil amplifier and their bearings in the extensions of the sidewalls of the barrel jacket are so designed that, besides offering a safe mounting of the amplifier for turning downwardly relative to the barrel jacket, so as to admit the extraction of the barrel when a change of barrel has to be effected, they will even make it possible to disassemble the amplifier from the barrel jacket without any use of tools.

An example of construction for a recoil amplifier according to the invention is illustrated on the drawing.

Figure 1 shows in side view, and partly in section, a recoil amplifier mounted on the front part of the barrel jacket of an automatic firearm and also shows further parts of the barrel section of the firearm.

Figure 2 shows the recoil amplifier and the front part of the barrel jacket, in top view,

Figure 3 shows chiefly the same parts as shown in Figure 1, but in position for extracting the barrel from the recoil amplifier, and

Figure 4 shows a cross section along lines IV—IV in Figures 1 and 2.

On the drawing, 10 is the barrel of an automatic firearm, 11 the barrel jacket and 12 the recoil amplifier. The barrel is bayonet locked in the receiver 13 and has a handle 14 by means of

2

which it may be turned around its axis for undoing the bayonet lock, whereafter it is moved forward, free of the receiver. The barrel jacket is open on top, allowing the barrel to be lifted out of the jacket. The amplifier is connected to the barrel jacket and forms a foremost bearing for the barrel. The connection between the amplifier and the barrel is as follows:

The amplifier has two horizontal, lateral pivots 15 arranged diametrically opposite one another and resting in bearings 16 in front extensions 17 of the sidewalls of the barrel jacket. The bearings 16 are so placed with respect to the forward end of the barrel jacket 11 that when the recoil amplifier 12 is pivoted by means of lateral pivots 15 in the bearings, only a small space 20 is left between said front face 18 of the barrel jacket and the rear face 19 of the amplifier. The recoil amplifier 12 is thus permitted to pivot with respect to said barrel jacket 11 around the pivots 15, which are positioned in the bearings 16 which are formed in slots in the front end of the barrel jacket.

The barrel 10, after having been turned around its axis in order to disengage the bayonet lock, and having then been moved forward angularly with respect to the barrel jacket 11 in order that it may be disengaged from the receiver, may then be turned on the pivots 15 of the recoil amplifier 12 to a position shown in Figure 3, in which the barrel can be freely withdrawn from the recoil amplifier, in no manner whatever obstructed by the receiver. When the barrel has been removed in this way, the amplifier will be positioned with its rear face 19 abutting against the front face 18 of the lower wall of the jacket, ready to have a fresh barrel inserted, which latter may next be lowered into the barrel jacket, thereafter carried back into the receiver and finally turned to be locked in the latter.

In the example shown on the drawing, the lateral pivots 15 of the recoil amplifier are not fully cylindrical but somewhat flattened at the rear side, whereby each of the said pivots projects only approximately halfway into its bearings 16 in the sidewall extension 17. At a short distance behind the bearings 16, another pair of bearings 21 is connected to the first named bearings through passage 22, reduced from below to a total height corresponding to the smallest diameter of the flattened pivots. From each of the bearings 21 to the top side of the wall extensions 17 there is at the inner side of said extensions a groove 23 of a depth corresponding to the length of the pivot 15. Thus it will be seen that, when the bar-

rel is extracted from the recoil amplifier in the manner explained above, and the amplifier thereafter has been turned around its pivots 15 in the bearings 16 to an upright position, the amplifier may be carried backwards with its pivots through the passages 22 to the rearmost bearings 21, and from there upwards through the grooves 23 and removed from the barrel jacket, which removal may be desirable for cleaning purposes.

Having thus described my invention, what I claim is:

1. In an automatic firearm including a recoil amplifier, a barrel jacket, and a barrel removably locked in said barrel jacket but readily removable therefrom by disengaging the locking means holding said barrel in said barrel jacket, rotating said barrel through an angle with reference to said barrel jacket, and withdrawing said barrel from said firearm by axial movement of said barrel, the combination with said barrel jacket of a recoil amplifier pivotally jointed to said barrel jacket at the forward end thereof, said recoil amplifier being pivoted to said barrel jacket by means of a plurality of pivots positioned adjacent the rearward end of said recoil amplifier so that it may be rotated at an angle with reference to said barrel jacket around said pivots when said barrel is being removed from said barrel jacket and said recoil amplifier, the connection between the end of said barrel positioned within said amplifier being substantially that of one cylinder closely embracing another cylinder, whereby recoil energy is more efficiently communicated from said amplifier to said barrel, and heat is more readily transferred between said last-mentioned members.

2. In an automatic firearm including a recoil amplifier, a barrel jacket, and a barrel removably locked in said barrel jacket but readily removable therefrom by disengaging the locking means holding said barrel in said barrel jacket, rotating said barrel through an angle with reference to said barrel jacket, and withdrawing said barrel from said firearm by axial movement of said barrel, the combination with said barrel jacket of a recoil amplifier pivotally jointed to said barrel jacket at the forward end thereof, said recoil amplifier being provided adjacent the rearward portion thereof with a pair of horizontally extending pivots positioned on opposite sides of said recoil amplifier, and a plurality of bearings for said pivots positioned in the forward end of said barrel jacket, said pivots being adapted to rotate in said bearings, whereby said recoil amplifier may be rotated with respect to said barrel jacket around the axis of said pivots to permit ready removal of said barrel from said barrel jacket and said recoil amplifier, the connection between the end of said barrel positioned within said amplifier being substantially that of one cylinder closely embracing another cylinder, whereby recoil energy is more efficiently communicated from said am-

plifier to said barrel, and heat is more readily transferred between said last-mentioned members.

3. In an automatic firearm including a recoil amplifier, a barrel jacket, and a barrel removably locked in said barrel jacket but readily removable therefrom by disengaging the locking means holding said barrel in said barrel jacket, rotating said barrel through an angle with reference to said barrel jacket, and withdrawing said barrel from said firearm by axial movement of said barrel, the combination with said barrel jacket of a recoil amplifier pivotally secured to said barrel jacket at the forward end thereof, said recoil amplifier being provided, adjacent its rearward portion, with a pair of horizontally extending pivots positioned on opposite sides of said recoil amplifier, said pivots being flattened on the side thereof nearest the rearward portions of said firearm so that one cross-sectional diameter thereof is less in extent than the cross-sectional diameter of said pivots between unflattened portions thereof, said barrel jacket being provided at the forward end thereof with a pair of interconnected bearings for each of said pivot pins, one pair being positioned on each side of said barrel jacket, and the bearings on each side of said barrel jacket being arranged axially of said barrel jacket, and in communication with each other through an opening which is larger than the lesser diameter of said pivots but smaller than the greater diameter of said pivots, there being also provided in said barrel jacket, above each of said rearmost bearings of each pair on each side of said barrel jacket, an opening in the upper surface of said barrel jacket through which said pivots may be drawn thus facilitating removal of said recoil amplifier from said barrel jacket, said recoil amplifier being adapted, when said pivots are in the forward bearings of each pair on each side of said barrel jacket, to rotate around the axis of said pivots with reference to said barrel jacket, thereby permitting removal of said barrel from said barrel jacket and said recoil amplifier.

AAGE FREDERIK CHRISTIAN HENCKEL.
